REFLECTOR AIMING DEVICE

Howard C. Mead and Clarence A. Michel, Anderson, Ind., assignors to General Motors Corporation, Detroit, Mich., a corporation of Delaware

Application May 4, 1934, Serial No. 723,833

3 Claims. (Cl. 240—41.6)

This invention relates to vehicle lamps and more particularly to an improved construction for mounting the reflector for proper adjustment in the casing.

5 When the casing of an automobile headlight has been secured to the body, it is necessary to provide some adjusting means for directing the beam to the proper position on the road. Various means have been used to change the position of 10 the reflector.

It is an object of this invention to provide an adjustable support for the reflector within the casing so that it may be tilted either up or down or toward one side or the other as may be desired.

15 It is also an object of this invention to provide a vertical adjustment for the beam that is accessible from the outside of the casing and which has indexing means to assist in setting the height 20 of the beam.

A further object is to provide a seal between the casing and the lens instead of the usual seal between the reflector and the lens which eliminates interference with the adjusting of the reflector.

25 In the drawings which form a part of this specification:

Figure 1 is a side elevation partly in section showing the reflector and its adjustments.

Figure 2 is a partial section taken on the line 30 2—2 of Figure 1 showing a detail of the adjusting screw which holds the reflector to the casing.

Figure 3 is a front view of the reflector.

Figures 4, 5 and 6 are details of the parts used in the adjustable means fastened to the lower 35 portion of the reflector.

Figures 7 and 8 are details of the parts used for supporting the two sides of the reflector.

Referring specifically to Figure 1, a headlight casing 1 is shown which is fastened to the headlight support by the bolt 2. The front of the headlight is covered by a lens 3 which is held in place by the rim 4. The rim 4 is provided at the top with a downturned lug 5 engaging an aperture in the top of the casing. The rim 4 is preferably of the contracting band type and is clamped about the casing by rotating turnbuckle 6. The casing 1 is bent in toward its central axis throughout its circumference to form a flange 7 and is then continued forward to form a lip 8 on said flange. A cork ring washer 9 is placed in the retainer formed by the flange and lip. A piece of flexible zinc 10 is wrapped around the outside perimeter of the cork to keep it in place.

A reflector 11, which holds the bulb 12, supplied 55 with current by the wire 13 is supported within

the casing at two points 14 and 15 on the horizontal axis of the face of the reflector. To these opposite points on the flanged edge extending at right angles to the axis of the reflector, are secured threaded lugs 16 as by rivets 17. The vertical flange 7 is drilled at points in line with the lugs for the insertion of screws 17', the heads of these screws being countersunk so that they will not injure the cork band. Between the lug and the back of the flange is placed a spring 18 to hold the two at a set distance apart, depending on the distance the screw is driven through the lug.

In the center, at the lowermost portion of the flange of the reflector, a small piece 19 is punched 15 and pressed out of the plane slightly to the front. A lever 20, which has one end bent at right angles to its longitudinal axis and then back upon itself as at 21 to form a clip, has a hole 22 on the outer face which engages the piece 19 to secure the two 20 together. The other end of the lever is curled up into a circle 22' and carries a small shaft serving as a pivot. This shaft fits inside two loops 23' which extend from a square nut 23. This nut is threaded upon a bolt 24. An angular supporting 25 member 25 is secured to the case at the bottom, the main axis of which runs at an angle to that of the casing. The bolt 24 engages the two upturned end portions of the member 25 and is rotatable therein. The bolt 24 is secured in the 30 member 25 by a cotter pin 26 at one extremity and by head 27 at the other. In assembling this unit the bolt 24 is inserted thru one of the upstanding ends of the member 25, then a spring 28 is slipped over the bolt, then the nut 23 is fed onto 35 the end and compresses the spring 28, then the outer end of the bolt is pushed thru the other upturned end of member 25 and the cotter pin 26 inserted to hold it secure. The under side of the bolt head has a series of radial grooves 29 40 which fit over a series of radial ridges 30 in the upturned end 31 of member 25 when the bolt is fastened in the member 25. When the bolt is turned, therefore, the ridges 30 will push the bolt head out until the next groove comes into position opposite the ridge when it will click into contact again.

It will be seen from the foregoing description that any adjustment of either of the side screws 17' will tend to tilt the reflector laterally since 50 these two screws are located on the horizontal axis. Also, any adjustment of the screw 24 will drive the nut 23, which pushes or pulls the lever 20, which in turn pushes or pulls the lower edge of the flange of the reflector. This rotates the 55

reflector about its horizontal axis and specifically about the two screws 11'.

The notches in the rear side of the head of bolt 24 assist in the vertical adjustment of the beam 5 of the headlight since the operator may count the number of notches turned and so obtain an index of the height of the beam. The notches also by engagement with the ridges 30 keep the reflector in adjustment by preventing the bolt from rotating 10 due to vibration.

It is also desired to point out that the usual cork ring seal is carried by the edge of the casing and does not contact with the reflector at any point. In this way any pressure that is exerted 15 by the lens upon this ring in no way affects the reflector.

It is therefore seen that we have provided an adjustable reflector for a headlamp which is adjustable both vertically and laterally, and which 20 has its vertical adjustment from the outside of the case and is provided with an indexing means. The novel suspension of the cork ring seal has been pointed out in the preceding paragraph.

We claim:

- 25 1. A headlight including a casing, a reflector positioned within the casing, means for resiliently mounting the reflector at the two opposite sides, and means for tipping the reflector about an axis passing through said mounting means comprising 30 a lever attached to the lowermost portion of the reflector, a nut pivoted to the other end of said lever and a bolt accessible from the outside of the casing to adjust the position of the nut, a bolt head upon said bolt, the underside of which is

radially grooved, a member against which this head bears which has a series of radial projections so that as the bolt is rotated a click will be heard as each projection is passed which will give an index as to the distance the bolt has been turned. 5

2. In a headlamp, a casing, an opening in one face of the casing, an inturned flange surrounding said opening, a lip on the flange, a reflector within said casing, resilient and adjustable means supporting the reflector from the flange at opposite points on its horizontal axis, adjustable means secured to the lowermost edge of the reflector for tipping the same and being accessible from the outside of the casing, a gasket carried by said flange and lip, a lens and means supporting the lens against the gasket whereby the lens presses tightly against the casing through the gasket but the reflector is free to tilt. 10 15

3. In a headlamp, a casing, a reflector resiliently and adjustably mounted in the casing at the opposite ends of its horizontal axis, means secured to the lowermost part of the reflector by which the latter may be tilted, said means including a strap secured to the reflector, a nut 25 pivotally secured to the strap, a bracket secured to and having a portion projecting through the casing, a pair of aligned openings in the bracket, a bolt extending through these and having its intermediate portion engaging the nut and a spring surrounding the bolt between the nut and the bracket to cause positive feed of the nut. 20
